Specification of Letters Patent. Patented Sept. 10, 1912.

Original application filed March 16, 1906, Serial No. 306,410. Divided and this application filed December 28, 1908. Serial No. 469,586.

To all whom it may concern:

Be it known that we, OTTO SCHÖNHERR, doctor of philosophy and chemist, and JOHANNES HESSBERGER, electrician, subjects, respectively, of the King of Saxony and the King of Prussia, residing at Fiska, Norway, have invented new and useful Improvements in Electrodes, which is an invention divided out of our application for Letters Patent filed March 16, 1906, Serial No. 306,410, and of which the following is a specification.

In Patent No. 930,238, dated August 3, 1909, of which the present application is a division, we have described the production of a new electrical phenomenon, namely long stable electric arcs. In the apparatus for the production of the said long stable electric arcs we use a new electrode which we have invented and which is the subject matter of the present application. The said long stable electric arcs are principally used for effecting reactions in gases and are generated in a furnace which is preferably tubular and through which a current of the said gases is suitably passed. Our new electrode is so arranged that, upon the one hand it can be cooled by the aid of a portion of the current of gas to be treated and on the other hand it is provided with a central rod which while wearing away itself when the apparatus is at work prevents the remainder of the electrode from suffering to any extent and which can be adjusted by being pushed forward whenever necessary.

In the accompanying drawings,—Figure 1 represents, in vertical section, a convenient form of our new electrode, which is represented in position in a short piece of tube. Fig. 2 represents, in vertical section, another convenient form of our electrode.

Referring to Fig. 1, the electrode is represented in position in a short piece of tube AB which by means of its upper flange can be attached to the tube or furnace in which the long arc is formed. The said electrode is insulated from the tube or furnace AB by means of insulating material EE. The electrode is made up of three parts: the hollow tube C, the head C₂, and the movable central rod C₃. The lower part of the tube AB constitutes an annular chamber surrounding the electrode. A part of the gas to be treated is forced into this chamber and

thence it enters the tube of the electrode 55 through openings F and passes along the said tube in the annular space surrounding the adjustable rod to the hollow head from which it issues through the opening F' as shown by the arrows. 60

A more efficient cooling can be effected by the use of water in the electrode instead of a part of the gases to be treated. In this case of course there must not be any openings from the head of the electrode into the furnace, but on the contrary an exit pipe must be provided so that the water may circulate in and out of the electrode without entering the furnace. This arrangement is shown in Fig. 2. C₁ is a tube, C₂ represents 70 the head, and C₃ the adjustable iron rod. Water is circulated through the tube C, entering at G and leaving at H, and taking the course indicated by the arrows. The water should be supplied through long india-rubber tubes and should be as pure as possible so as to prevent large quantities of the current going directly to earth through the water. E represents insulating material. 75

Now what we claim is:

1. An electrode comprising a hollow tube leading to a hollow head through which runs a central adjustable rod movable relatively to the remaining parts of the electrode, the said tube and head containing 85 openings for the circulation of cooling fluid.

2. An electrode comprising a rod of conducting material in a hollow holder, movable relatively to this holder, and means for cooling the said adjusting rod and holder. 90

3. In conjunction with an electric furnace for gas-reactions an electrode insulated from the furnace, a chamber at the end of said furnace not in communication with it, means for forcing a cooling fluid into the 95 said chamber, openings from said chamber into the hollow tubular stem of the electrode, an annular space within the said stem surrounding a rod of conducting material and leading to the hollow head of the said 100 electrode, and means for withdrawing the said cooling fluid from the electrode after it has become heated.

4. In conjunction with an electric furnace for gas reactions an electrode insulated from the furnace, a chamber at the end of said furnace, means for forcing gas into said chamber, openings from said chamber into

the hollow tubular stem of the electrode, an annular space within said tubular stem surrounding an adjustable rod of conducting material and leading to the hollow head of the electrode and openings from said hollow head to the body of the furnace.

In testimony whereof we have hereunto

set our hands in the presence of two subscribing witnesses.

OTTO SCHÖNHERR.

JOHANNES HESSBERGER.
